BERT E. DRAKE, OF ROCKVILLE CENTER, NEW YORK, ASSIGNOR OF ONE-HALF TO
HORACE D. TRACY, OF ROCKVILLE CENTER, NEW YORK.

DISPLAY DEVICE.

Application filed September 1, 1926. Serial No. 133,038.

My invention relates to a display device for exhibiting to the trade shoes or other articles of apparel, the invention having particular usefulness for the display of 5 shoes in which different textures of materials are employed. My device is designed to very materially reduce the number of sample shoes required to be carried by a salesman for the display of the goods in a wide variety.

The general object of my invention is to provide a device of the indicated character whereby the various colored materials and materials of various character or texture 15 may be laid over a dummy simulating a section of a shoe, for example, and so clamped in position that the material will be displayed smoothly without puckering or wrinkling, so as to indicate to a dealer the 20 exact appearance of a shoe embodying the particular materials, so that a shoe of a given last may be displayed in various colors as it will appear when made up of various materials.

25 The nature of my invention and its distinguishing features and advantages will clearly appear as the description proceeds.

Reference is to be had to the accompanying drawings forming a part of this specification, it being understood that the drawings are merely illustrative of a practical 30 example of the invention.

Figure 1 is a plan view of a display device embodying my invention, showing the 35 same in position with the clamp closed against the base;

Figure 2 is a cross-section thereof, indicated by the line 2-2 of Figure 1, showing the material held in position by the clamp 40 plate;

Figure 3 is a front elevation of the display device with the clamp in raised position.

In carrying out my invention in accordance with the illustrated example, a base 10 is provided, essentially flat and rigid, which said base has thereon a dummy 11, which in the present example simulates a lady's shoe. In the preferred form of the invention, 45 advantageously the base 10 and the dummy 11 are formed integrally by stamping the same up from a metal plate. The numeral 12 indicates a clamping plate hinged along one edge by suitable hinges 13 so that said

clamping plate may be swung to a raised 55 position as in Figure 3, or lowered on to the base 10 for clamping leather, woven fabric or the like, indicated at A in Figure 2.

In the clamp plate 12 is a cut-out simulating the profile of a shoe, for example, to be displayed, and with said plate in the lowered position the dummy 11 will project through said opening 14.

As will be observed from Figure 1, 65 which shows the clamp plate in the lowered position, the defining edge of the opening 14 is spaced from dummy 11 at certain portions, a greater distance than the remaining portions, as indicated at 114 adjacent the sole of the dummy 11. Said opening spaced an increased distance from the dummy 11 is adjacent to the point of greatest projection, as indicated at 111, which is the sole portion of the dummy. 70 The result is that these edge portions of opening 14, lying closely to dummy 11, will draw the material A tightly over the dummy and the edge portions 114 will similarly draw the material A smoothly and will accommodate the material in a manner to prevent wrinkling.

An important feature in effecting the tight clamping of the material A over the dummy on to the base 10 and properly 85 straightened over the dummy 11, is the edge formation of the base and clamp plate. The edges 15 of the base, it will be seen, are rounded, and edges 16 of clamp plate 12, except the hinge edge, are rounded and deflected rearwardly, considering the clamp plate in its clamping position as in Figure 2. The result is not only that the fabric is 90 tightly held in the manner for the most effective display, but the edge portion or surplus portion of the fabric is deflected rearwardly so that no area of the fabric A except that which has been draped over the dummy 11 appears to the eye, to lessen the effective display of the fabric on the dummy.

With the above described device wide variance in a shoe of a given last may be effectively displayed in a manner to show the actual appearance with various colors and 95 of various materials.

Different portions of the shoe may be made up of different materials in different 100 105

colors by laying over the dummy 11 different woven fabrics, leather, suede or the like, so that one dummy representing a given last enables a dealer to judge of the same shoe 5 when made up in a wide variety of materials.

I would state, furthermore, that I do not limit myself strictly to the exact details herein illustrated, since, manifestly, the same 10 may be considerably varied without departing from the spirit of the invention as defined in the appended claims.

I claim:

1. A device for exhibiting shoes and other articles, including a base having a dummy 15 projecting therefrom and simulating the article to be exhibited, and a clamp adapted to be lowered on to the base for clamping materials laid over said dummy or disposed in a raised position away from the dummy, 20 said clamp having a cut-out conforming to the dummy, certain edges defining the cut-out being spaced a greater distance from the dummy than other defining edge portions

of the cut-out, when the clamp is disposed against the base. 25

2. A display device including a base having a dummy thereon simulating an article and a clamp adapted to be disposed against the base and having an opening for the dummy to project through, for the clamping 30 of material on to the base and extending over the dummy, the said plate having edge portions deflected in a direction toward the back of the base.

3. A display device including a base having a dummy thereon simulating an article and a clamp adapted to be disposed against the base and having an opening for the dummy to project through, for the clamping 35 of material on to the base and extending over the dummy, the said plate having edge portions deflected in a direction toward the back of the base, said base adjacent said edge portions of the clamp being rounded. 40

BERT E. DRAKE.
